UNITED STATES PATENT OFFICE

98,046

DESIGN FOR A TOBACCO PIPE

Montague Henry Barling, Camden Town, London, England, assignor to the firm B. Barling & Sons, London, England, a partnership composed of Walter Frederick Barling, Walter William Barling, and said Montague Henry Barling

Application January 3, 1935, Serial No. 54,705
In Great Britain December 14, 1934

Term of patent 14 years

To all whom it may concern:

Be it known that I, Montague Henry Barling, a subject of the King of Great Britain, residing at 9, 10, and 11 Park Street, Camden Town, London, N. W. 1, England, have invented a new, original, and ornamental Design for a Tobacco Pipe, of which the following is a specification, reference being had to the accompanying drawing, forming part thereof.

Figure 1 is a perspective view; and

Figure 2 is a side view of a tobacco pipe embodying my new design.

The dominant feature of my invention resides in the configuration of the stem which stem when viewed from the side is long and substantially flat and consists of a relatively short narrow ferrule member having angular shoulders with the straight sides thereof merging with the flat stem, which stem is slightly tapered toward its end, terminating in the mouthpiece.

I claim:

The ornamental design for a tobacco pipe, substantially as shown and described.

MONTAGUE HENRY BARLING.
